UNITED STATES PATENT OFFICE.

ANTHONY VASSELLI, OF NEWARK, NEW JERSEY, ASSIGNOR, BY MESNE ASSIGNMENTS, TO GENERAL PHONOGRAPH CORPORATION, OF NEW YORK, N. Y., A CORPORATION OF NEW YORK.

TURNTABLE FOR TALKING-MACHINES.

1,399,171.

Specification of Letters Patent.

Patented Dec. 6, 1921.

Application filed October 9, 1919. Serial No. 329,480.

To all whom it may concern:

Be it known that I, ANTHONY VASSELLI, a citizen of the United States, and a resident of the city of Newark, county of Essex, and 5 State of New Jersey, have invented a certain new and useful Improvement in Turn-tables for Talking-Machines, of which the following is a specification.

My invention relates to turn-tables for 10 talking machines, and has for its object to produce a device of the character described, which will be light in weight, cheap to manufacture, ornate in appearance, and from which the record disk may be easily removed.

15 My invention relates to means for securing a pad to turn-tables of disk talking machines and the production of means so that such pad will not become disarranged in use and to prevent the unraveling of the fabric 20 constituting the pad.

A further object of the invention is to produce a device of the character described, which is extremely simple in construction, 25 neat and attractive in appearance, thoroughly reliable and efficient in its purpose, and inexpensive to manufacture.

With these and other objects in view to be 30 more fully set forth hereinafter, the invention consists in the novel construction, combination of elements, and arrangement of parts which will be exemplified in the construction hereinafter described in the specification and illustrated in the accompanying drawings considered together or separately.

35 The inventive idea involved is capable of receiving a variety of mechanical expressions, some of which for the purpose of illustrating the invention, are shown in the accompanying drawings.

40 The invention will be first described in connection with the accompanying drawings, wherein similar reference characters are used to designate corresponding parts throughout the several views, and then more 45 specifically defined and indicated in the appended claims.

In the drawings,—

Figure 1 is a top plain view of a turn-table made in accordance with my invention; 50 Fig. 2 is a side elevation of the same; Fig. 3 is a sectional view of the device at one stage of the operation of forming the turn-table;

Fig. 4 is a fragmentary side elevation

partly in section showing a further step in 55 the manufacture; and

Fig. 5 is a detail section showing a modification.

The turn-table 1 is composed of a disk of cold rolled steel which is first cut to circular 60 form, and then stamped with a slight depression 2 at its center and with a perforation 3 at the center of the depression or of the disk proper.

The periphery of the disk is then turned 65 downwardly to form the member 4 at an angle of approximately 60°, and then upwardly to form the member 5.

A hub 6 having a tapered bore 7 is secured to the under side of the center by 70 rivets 8 or otherwise.

The rim or member 5 is now bent over 75 parallel to the member 4, and a cover 9 of velvet or other suitable material is secured to the top of the turn-table by means of glue or otherwise. The edge of the cover or pad 8 is inserted in the annular space between the members 4 and 5.

In the modification shown in Fig. 5, the 80 rim 5 does not reach to the surface of the turn-table, and a portion of the cover 9 is visible from the side.

No part of the device projects above the 85 surface of the turn-table, and the record disk, even should it be of greater diameter than the turn-table, will have a solid backing for its entire area.

The side of the turn-table is inclined as shown. This not only adds to the appearance of the device, but with a turn-table having 90 its greatest diameter, the same as that of the record for which it is designed, will leave a space beneath the edges of the record disk whereby the disk may be easily removed from the turn-table. For 12 inch 95 records a turntable having its greatest diameter, that is the bottom of the rim 4—5 of 12 inches, the record will project about $\frac{1}{4}$ inch all around the turn-table.

If desired, the cover may be placed in 100 position when the device is in the position shown in Fig. 3 and the rim 5 bent over on the edge of the cover.

A turn-table made of flat cold rolled steel 105 is cheaper to make than one of cast iron, as it takes but two operations, one to form the table, and the other to press over the inclined wall. The inclined wall is of great advan-

tage in fastening the fabric. It is impossible to properly fasten the fabric in a device having straight grooves, as there is a great tendency for the fabric to crack when 5 so fastened.

In accordance with the provisions of the patent statute, I have described the principle of my invention together with the apparatus which I now consider to represent the best 10 embodiment thereof, but I desire it understood that my invention is not confined to the particular form of apparatus herein shown and described, the same being merely illustrative, and that the invention can be carried out in other ways without departing from the spirit of my invention, and, therefore, I claim broadly the right to employ all 15 equivalent instrumentalities coming within the scope of the appended claims, and by 20 means of which objects of my invention are attained, and the new results accomplished, as herein set forth, as it is obvious that the particular embodiments herein shown and described are only some of many that can be 25 employed to attain these objects and accomplish these results.

Having now described my invention, what I claim and desire to secure by Letters Patent is as follows:

- 30 1. A turn-table for talking machines, comprising a disk, there being a flange at the periphery of the disk, said flange having a groove therein, said groove being at an angle to the surface of the disk.
- 35 2. A turn-table for talking machines, comprising a disk stamped from sheet material, there being a flange at the periphery of the disk, said flange having a groove therein,

said groove being at an angle to the surface of the disk.

3. A turn-table for talking machines, comprising a disk stamped from sheet material, there being a flange at the periphery of the disk, said flange having a groove therein, said groove being at an obtuse angle to the 45 surface of the disk, said groove being open at the top.

4. A turn-table for talking machines, comprising a disk stamped from sheet material, there being a flange at the periphery of the disk, said flange having a groove therein, said groove being at an obtuse angle to the 50 surface of the disk, said groove being open at the top, and a cover for the disk, the periphery of said cover resting within the 55 groove.

5. A turn-table for talking machines, comprising a disk stamped from sheet material, there being a flange at the periphery of the disk, said flange being at an angle relatively 60 to the surface of the disk, a second flange joined thereto at the bottom, there being a space between the flanges, said space being open at the top.

6. A turn-table for talking machines, comprising a disk, there being a flange at the periphery of the disk, said flange being at an angle relatively to the surface of the disk, a second flange joined thereto at the bottom, there being a space between the flanges, and 70 a cover for the disk, the periphery of said cover resting within the space.

This specification signed this 15th day of September, 1919.

ANTHONY VASSELLI.
